CLAIM

[21] Appl. No.: 128,516

The ornamental design for a manual sunroof latch, as shown.

DESCRIPTION

FIG. 1 is a perspective view of a manual sunroof latch handle showing our new design;

FIG. 2 is a perspective view thereof of the side and end opposite to that shown in FIG. 1;

FIG. 3 is an end elevation view thereof; and

FIG. 4 is an opposite end elevation view thereof.
